UNITED STATES PATENT OFFICE

120,355

DESIGN FOR A FINGER RING

Sam J. Portnoy, Milwaukee, Wis., assignor of one-fourth to Frank O. Kloiber, and one-fourth to Sidney J. Herzberg, Milwaukee, Wis.

Application March 4, 1940, Serial No. 90,813

Term of patent 7 years

To all whom it may concern:

Be it known that I, Sam J. Portnoy, a citizen of the United States, residing at Milwaukee, in the county of Milwaukee and State of Wisconsin, have invented a new, original, and ornamental Design for Finger Rings, of which the following is a specification, reference being had to the accompanying drawing, forming part thereof.

Figure 1 is a top plan view of a finger ring
showing my new design;

Figure 2 is an edge view looking toward the open end of the horse-shoe;

Figure 3 is a side elevational view, and Figure 4 is a view opposite of that shown in Figure 2.

I claim:

The ornamental design for a finger ring, as shown.

SAM J. PORTNOY.
